UNITED STATES PATENT OFFICE.

LOUIS BARGMANN, OF BROOKLYN, NEW YORK.

CHRISTMAS-TREE HOLDER.

1,198,694.

Specification of Letters Patent. Patented Sept. 19, 1916.

Application filed April 5, 1916. Serial No. 89,042.

To all whom it may concern:

Be it known that I, LOUIS BARGMANN, a citizen of the United States, and a resident of Brooklyn, in the county of Kings and State of New York, have invented certain new and useful Improvements in Christmas-Tree Holders, of which the following is a specification.

This invention relates to a Christmas tree holder which is adapted to securely support without trimming, trees having stems of different thicknesses, or which are provided with knots or other irregularities at their base.

15 In the accompanying drawing: Figure 1 is a plan of a Christmas tree holder embodying my invention, and Fig. 2, a side elevation partly in section thereof.

The device comprises essentially, a base 1, shown to be made cruciform, and to be supported upon feet 2. To base 1 are hinged at 3, two sets of diametrically disposed arms or braces 4, which will normally assume an inclined position. The two opposed members 25 of each set of braces carry a flexible strap 5, which is attached to the inner ends of the braces, and is of such a length as to sag downwardly therefrom to a considerable extent. With the embodiment shown, there 30 will thus be provided two straps 5, that cross at their center or lowermost points, where they are apertured for the reception of a depending screw bolt 6. Upon base 1 is centered a flanged socket 7 provided with a squared bore 8. Screw bolt 6, passes through this bore and thence likewise through base 1, the lower exposed end of the bolt carrying a winged nut 9.

In use, braces 4, are swung outwardly, the 40 stem 10 of the Christmas tree is introduced

between straps 5, and then nut 9 is turned to draw the straps downward into the socket, and thus tighten their hold upon the stem, while the braces are simultaneously swung inward against the latter. In this way, 45 the tree will be securely mounted without regard to its thickness, the holder being adapted to fit all stems, the diameters of which are within the range of the braces. By slackening nut 9, the braces may be manually swung 50 outward, to open up the straps and thus cause the latter to relinquish their hold on the tree.

I claim:

1. A holder of the character described, 55 comprising a base, a pair of braces hinged thereto, a sagging flexible strap carried by the braces, and adapted to be passed underneath the article to be supported, and means for drawing said strap centrally toward the 60 base.

2. A holder of the character described, comprising a base, sets of diametrically disposed braces hinged thereto, a plurality of intersecting sagging flexible straps carried 65 by the braces and adapted to be passed underneath the article to be supported, and a member depending from the centers of the straps and adapted to draw said straps toward the base. 70

3. A Christmas tree holder, comprising a base, sets of diametrically disposed braces hinged thereto, a plurality of intersecting flexible straps carried by the braces, a socket mounted upon the base, a bolt depending 75 from the straps and passing through the socket, said bolt likewise engaging the base, and a nut mounted on the bolt.

LOUIS BARGMANN.
